(57) **CLAIM**

The ornamental design for a one-piece footie with arm fasteners, as shown and described.

DESCRIPTION

FIG. 1 is a front perspective view of a one-piece footie with arm fasteners.

FIG. 2 is a front elevational view of the one-piece footie with arm fasteners shown in FIG. 1.

FIG. 3 is a rear elevational view of the one-piece footie with arm fasteners shown in FIG. 1.

FIG. 4 is a right side elevational view of the one-piece footie with arm fasteners shown in FIG. 1.

FIG. 5 is a left side elevational view of the one-piece footie with arm fasteners shown in FIG. 1.

FIG. 6 is a top plan view of the one-piece footie with arm fasteners shown in FIG. 1.

FIG. 7 is a bottom plan view of the one-piece footie with arm fasteners shown in FIG. 1.

FIG. 8 is a front elevational view of the one-piece footie with arm fasteners shown in FIG. 1 with a front thereof closed.

FIG. 9 is a front perspective view of an alternative one-piece footie with arm fasteners.

FIG. 10 is a front elevational view of the one-piece footie with arm fasteners shown in FIG. 9.

FIG. 11 is a rear elevational view of the one-piece footie with arm fasteners shown in FIG. 9.

FIG. 12 is a right side elevational view of the one-piece footie with arm fasteners shown in FIG. 9.

FIG. 13 is a left side elevational view of the one-piece footie with arm fasteners shown in FIG. 9.

FIG. 14 is a top plan view of the one-piece footie with arm fasteners shown in FIG. 9.

FIG. 15 is a bottom plan view of the one-piece footie with arm fasteners shown in FIG. 9; and,

FIG. 16 is a front elevational view of the one-piece footie with arm fasteners shown in FIG. 9 with a front thereof closed.

The features shown in dashed lines shown throughout the drawings represent unclaimed portions of the one-piece footie with arm fasteners and form no part of the claimed design.

1 Claim, 12 Drawing Sheets
